UNITED STATES PATENT OFFICE.

CLINTON H. HENDERSON, OF MARTINEZ, CALIFORNIA.

TAMPER AND TEMPLET FOR CONCRETE WORK.

1,220,986.

Specification of Letters Patent. Patented Mar. 27, 1917.

Application filed June 9, 1916. Serial No. 102,724.

To all whom it may concern:

Be it known that I, CLINTON H. HENDERSON, a citizen of the United States, residing at Martinez, in the county of Contra Costa and State of California, have invented certain new and useful Improvements in Tamers and Templets for Concrete Work; and I do hereby declare the following to be a full, clear, and exact description of the invention, such as will enable others skilled in the art to which it appertains to make and use the same.

This invention relates to a tamper and templet for use in concrete work, and the primary object of the invention is to provide a device of this nature, which will materially save labor in the leveling and puddling of concrete on highway work, in that the device is constructed so that two men can level, tamp, puddle and finish an entire road bed.

Another object of this invention is to provide a tamper and templet for concrete work which is very simple in construction, and comprises a body plate which has a templet and tamping plate secured to the under side of the same, which templet or tamping plate is curved to provide the proper crown in the middle of the road bed to permit of the proper draining of the same, and further to attach handles to each end of the body of the tamper and templet through the medium of which the same is operated.

With the foregoing and other objects in view this invention consists in such novel features of construction, combination and arrangement of parts as will be hereinafter more fully described, illustrated in the accompanying drawings and claimed.

In describing the invention in detail reference will be had to the accompanying drawings wherein like characters designate like or corresponding parts throughout the several views, and in which:—

Figure 1 is a side elevation of the improved tamper and templet.

Fig. 2 is a top plan view of the tamper and templet, and

Fig. 3 is a fragmentary perspective of the body of the tamper and templet.

Referring more particularly to the drawings, 1 designates the body plate or bar of the tamper and templet, which is constructed of wood or analogous material, and has its under surface 2 cut concave as clearly shown in Fig. 1 of the drawings. A me-

tallic plate 3 is secured to the under surface 2 of the body 1 by means of bolts or analogous fastening devices 4, the heads 5 of which are countersunk in the plate 3. 60 The plate 3 is wider than the width of the bottom of the body 1, and being secured to the under surface or bottom of the body 1, it is concavely curved, for giving the proper crown or raise to the middle of a road bed. 65 The metallic plate 3 has its ends 6 upturned, and secured to the end of the body 1. The portions 7 of the plate 5 which are adjacent to the upturned ends 6 are positioned in horizontal planes and are adapted for riding upon the upper surface of the wooden form (not shown) into which the concrete is placed during the formation of the concrete road bed, side walk or the like.

The body 1 is provided with recesses 8 formed in its sides at its end, diagonally through which recesses the lower end of the handles 9 extend. The handles 9 extend upwardly and outwardly from the body 1 and diverge as clearly shown in Fig. 2 of the drawings being braced intermediate their ends by suitable braces 10. The outer upper ends 11 of the handles 9 are bent substantially at right angles to the main portions of the handles to facilitate manipulation of 85 the tamper and templet. Braces 14 are secured to the sides of the body 1 near the ends of the same and they are also attached to the handles 9 as clearly shown in Fig. 1 of the drawings, for bracing the latter.

In the operation of the improved tamper and templet; the handles 9 are gripped by an operator; one at each end of the tamper and templet, and by raising and dropping the ends alternately, it will bring about that condition for concrete known as "puddling" leaving the surface of the road bed in a finished and smooth condition, properly forming the crown in the middle of the road bed and the proper tapering for drainage purposes, thereby eliminating a tedious and expensive method of tamping and finishing a road bed with the old or ordinary tamper and shovel method.

In reducing the invention to practice, certain minor features of construction, combination and arrangement of parts may be altered to suit practical conditions provided such alterations are comprehended within the scope of what is claimed.

What is claimed is:

1. In a tamper and templet for concrete

work, a body adapted to extend entirely across the surface being worked upon, said body having its lower edge cut concavely, a metallic plate detachably secured to said concaved lower edge, and handles attached to the ends of said body and extending upwardly and outwardly therefrom, said handles being arranged in diverging pairs.

2. In a tamper and templet for concrete work, a body adapted to extend entirely across the surface to be worked upon, said body having its lower bottom edge cut concavely, a metallic plate secured to said concaved edge, said plate being wider than said body and projecting upon opposite sides of the body.

3. In a tamper and templet for concrete

work, a body adapted to extend entirely across the surface to be worked upon, said body having its lower bottom edge cut concavely, a metallic plate secured to said concaved edge, said plate being wider than said body and projecting upon opposite sides of the body, the ends of said plates being upturned and secured to the ends of said body, the portions of said plates adjacent to said upturned end being positioned in horizontal plane.

In testimony whereof I affix my signature in presence of two witnesses.

CLINTON H. HENDERSON.
